(57) **CLAIM**

The ornamental design for a cooling pad, as shown and described.

DESCRIPTION

FIG. 1 is a perspective top and side view of a cooling pad according to the present invention

FIG. 2 is a top view of the cooling pad according to FIG. 1.

FIG. 3 is a bottom view of the cooling pad according to FIG. 1.

FIG. 4 is a side view of the cooling pad according to FIG. 1.

FIG. 5 is an opposite side view of the cooling pad according to FIG. 1.

FIG. 6 is an end view of the cooling pad according to FIG. 1; and,

FIG. 7 is an opposite end view of the cooling pad according to FIG. 1.

The portions of the cooling pad shown in broken lines form no part of the claimed design.

The item shown in the Figures is a medical device provided in the form of a cooling pad for cooling a head.
